(57) **CLAIM**

The ornamental design for a tile frame, as shown and described.

DESCRIPTION

FIG. 1 is a perspective view of the tile frame showing our new design;

FIG. 2 is a front elevational view thereof;

FIG. 3 is a rear elevational view thereof;

FIG. 4 is a left side elevational thereof;

FIG. 5 is a right side elevational view thereof;

FIG. 6 is a bottom view thereof;

FIG. 7 is a top view thereof;

FIG. 8 is a front elevational view of the tile frame shown without the tiles; and,

FIG. 9 is a cross-sectional view of the tile frame of FIG. 1. The dash-dot broken lines in FIG. 3 are for the purpose of illustrating the cross-sectional cut and form no part of the claimed design.
